MEANS FOR MAKING CONCRETE STRUCTURES IN FORMS

William A. Whiting, Southgate, Calif., assignor to American Concrete and Steel Pipe Company, a corporation of Delaware

Application May 22, 1936, Serial No. 81,215

4 Claims. (Cl. 25—1)

This invention relates to an improved means of working concrete in forms having considerable height, wherein a rod of comparatively small cross sectional area is rotated in the concrete adjacent to the form thus providing a smooth and dense concrete finished product, especially in that portion of the concrete against the form, something which, to my knowledge cannot be successfully done by any other method. In concrete structures which have been poured in forms the face of the concrete is ordinarily pitted with holes formed by air and water pockets. This is undesirable, particularly in the case of concrete pipe sections where it is desirable to have a smooth compact surface on the pipe.

I have found that in the use of such rods in forms of great height, where the concrete is necessarily of great depth, many difficulties are encountered in the operation of the rods. The great mass of concrete through which the rod operates slows up the lateral movement of the rod, thus making the operation a lengthy one as compared to the case where the rod is working through a relatively shallow body of concrete. There is also a tendency for the rod to creep away from the side of the form where there is a great depth of concrete.

It is, therefore, an object of my invention to overcome the difficulty of operating such tools of the rotating rod type in deep concrete by providing a tool capable of performing efficiently under such adverse conditions. Ordinarily these rods are of various forms in cross section, being round or square or of spiral form and are usually made of iron either pointed or squared off at the lower end. I have found that by using a ball on the lower end of the rod, preferably of greater diameter than the diameter of the rod, the ball having a hardened face as distinguished from the relatively softer iron of the rod, and that by employing a flexible rod or one having one or more universal joints therein, I am able to overcome all of the difficulties of the prior devices. The use of the ball on the end of the rod enables the rod to progress through the concrete laterally much easier and at a much greater speed than was formerly possible. The ball in conjunction with the flexible rod materially increases the efficiency of this type of device. The ball, or an enlarged rounded end portion, may also be used with a rod not having joints and even in such adaptation better results are obtained than was formerly possible with common forms of rods. For use in concrete forms of great height, such as for instance pipe sections of eighteen or twenty

feet, I prefer to use the form of rod having projections on one side which propel the rod laterally through the concrete when it is revolved. The rod moves laterally along the form due to the fact that during its rotation the off-center portions of the rod successively engage the concrete next to the form and the concrete in the main body of the material, and due to the fact that there is less resistance in the concrete next to the form than in the concrete near the center of the form, the rod propels itself along adjacent to the side of the form thoroughly tamping the concrete and removing the air and water bubbles from that portion of the concrete surface adjacent the form.

Referring to the drawing which is for illustrative purposes only;

Fig. 1 is a fragmentary sectional elevation showing the position of the rod in the concrete;

Fig. 2 is a diagrammatic elevation showing the position of the rod by dotted lines in the concrete;

Fig. 3 is a sectional plan view taken on line 3—3 of Fig. 2 showing the rod adjacent the outer form;

Fig. 4 is a sectional plan similar to Fig. 3 showing the rod adjacent the inner form;

Figures 5, 6, 7 and 8 are elevational views of different forms of rods.

With further reference to the drawing, numeral 10 indicates the outer form and 11 the inner form, both being circular and mounted on a base 12, the concrete being designated at 13. 15 designates the rod of the type shown in Fig. 5, having a joint 16 and a ball 17 at its lower end. 18 designates a motor, or other means for rotating the rod having handles 19 for the convenience of the operator. 20 designates reinforcing members in the concrete. It will be noted that the rod of my invention may be easily operated where the reinforcing members may obstruct considerable portions of the concrete. 21 indicates a universal joint on the motor shaft although a flexible cable drive may be employed in place of the universal joint, the rod being connected to the motor by means of a socket and set screw 22.

Fig. 2 diagrammatically illustrates the lateral position of the rod during operation, showing that the rod is slightly bowed and operates at an angle away from the vertical and in the direction of the arrow shown. While the form of rod shown in Fig. 5 has but one joint therein, I may use a number of joints in the rod or I may use a flexible rod as shown in Fig. 6 having a ball or rounded end 17.

The forms of rods shown in Figs. 7 and 8 show

the forms particularly adapted for use in deep concrete and are what I have termed offset on one side of the vertical axis of the rod.

In Fig. 6, 25 indicates an offset lower end on the 5 rod 15 terminating in a ball 17 and in Fig. 7 I have shown a similar rod provided with a block or projection 26 on the same side of the rod as the offset portion. The ball indicated at 17 may be made of any desirable material, but should preferably have a hard surface in order to prevent undue wearing of that portion.

In using my rod made in the forms above described the ball on the end of the rod rides on the base 12 of the form structure and rolls against 15 the vertical form. By placing the rod in the concrete with the lower ball end of the rod in the lead by exerting a slight pressure on the upper end of the rod the rod bends as shown in Figs. 2, 3 and 4 and travels forwardly in the direction of 20 the arrows in Figs. 2, 3 and 4, the rod following the form as there is less resistance in the concrete against the form than in the body of the concrete. I have found that the offset rod as shown in Fig. 6 and the rod as shown in Fig. 7 25 with the block or projection 26 causes the rod to propel itself through the concrete due to the difference in density of the concrete against the form and in the body.

With the use of all forms of rod shown herein 30 I find that the face of the concrete is firm and compact and free of holes which as heretofore noted is particularly desirable in concrete pipe construction and in addition to the production of a finished surface I have found that the action 35 of the rod due to its rotation causes the body of concrete to become more compact or dense. This latter effect mentioned of compacting the body of the concrete as well as the face of the concrete is an important feature and while such effect to

some extent takes place during the movement of the rod against the inner face of the form it is to be understood that the rod may be moved throughout the body of the concrete for compacting the entire body of the concrete. In using the 5 rods, above described, I have found that a whipping action takes place which is more pronounced when the rod is bent as shown in Figs. 2, 3 and 4. This whipping action of the rods thoroughly agitates the concrete and relieves the concrete of 10 voids and air pockets resulting in a dense body of concrete.

I claim as my invention:

1. A device for producing a smooth dense surface on concrete deposited against forms comprising: a flexible rod; projections on said rod at one side thereof; a ball on the lower end of the rod; and means for rotating said rod on its longitudinal axis in the concrete adjacent the form. 15

2. A device for producing a smooth dense surface on concrete deposited against forms comprising: a flexibly jointed rod; a ball on the end of the rod; and means for rotating said rod on its longitudinal axis in the concrete adjacent the form. 20

3. A device for producing a smooth dense surface on concrete deposited against forms comprising: a flexibly jointed rod; said rod having its lower end offset and having projections on the offset side of the rod; and a round hardened end 30 on the offset end of the rod.

4. The method of compacting a body of concrete in a form which consists in inserting a flexible rod into the concrete the lower end of the rod engaging the bottom of the form, rotating the rod 35 and exerting sufficient pressure on the top of the rod to cause the same to bend between its ends thereby producing a whipping action of the rod.

WILLIAM A. WHITING.
